(57) **CLAIM**

The ornamental design for a cassette sterilizer, as shown and described.

DESCRIPTION

FIG. 1 provides a left perspective view of a first embodiment of cassette sterilizer.

FIG. 2 provides a right perspective view of a first embodiment of cassette sterilizer.

FIG. 3 provides a front elevational view of a first embodiment of cassette sterilizer.

FIG. 4 provides a left elevational view of a first embodiment of cassette sterilizer.

FIG. 5 Provides a top plan view of a first embodiment of cassette sterilizer.

FIG. 6 provides a left perspective view of a second embodiment of cassette sterilizer.

FIG. 7 provides a right perspective view of a second embodiment of cassette sterilizer.

FIG. 8 provides a front elevational view of a second embodiment of cassette sterilizer;

FIG. 9 provides a left elevational view of a first embodiment of cassette sterilizer; and,

FIG. 10 Provides a top plan view of a second embodiment of cassette sterilizer.

The broken lines showing the body of the cassette sterilizer are for illustrative purposes only and form no part of the invention.
